UNITED STATES PATENT OFFICE.

HOWARD F. JOHNSON, OF CLEVELAND, OHIO, ASSIGNOR TO THE BROWNING COMPANY, OF CLEVELAND, OHIO, A CORPORATION OF OHIO.

DIFFERENTIAL BRAKE.

1,393,135.

Specification of Letters Patent. Patented Oct. 11, 1921.

Application filed November 7, 1919. Serial No. 338,454.

To all whom it may concern:

Be it known that I, HOWARD F. JOHNSON, a citizen of the United States, resident of Cleveland, county of Cuyahoga, and State 5 of Ohio, have invented new and useful Improvements in Differential Brakes, of which the following is a specification, the principle of the invention being herein explained and the best mode in which I have contemplated 10 applying that principle, so as to distinguish it from other inventions.

My invention relates to differential brakes. Particularly the invention relates to a brake of this character which will act automatically 15 to release or set a brake band upon the reversing of the direction of movement of the power-driven mechanism to which the brake drum is connected. My improved brake is of general application, but I shall 20 illustrate the principle thereof by means of showing and describing an embodiment of the same as applied to hoisting apparatus.

The annexed drawings and the following description set forth in detail certain means 25 embodying my invention, the disclosed means, however, constituting but one of the various mechanical forms in which the principle of the invention may be applied.

In said annexed drawings:

30 Figure 1 represents a side elevation of my improved brake applied to hoisting apparatus, fragmentary portions of the latter only being shown, the view showing the position of the several parts during the hoisting of the load; Fig. 2 represents a plan view taken in the planes indicated by the lines II—II, Fig. 1.

Fig. 3 represents an elevation of the parts shown in Fig. 1 when the brake is set to 40 suspend the load; and Fig. 4 represents an elevation of the same parts when the brake is released so that the load may be lowered.

Referring to the annexed drawings, there 45 is indicated by the ordinal 1 a drum upon which a hoisting cable is adapted to be wound to lift a load by means of coöperating mechanism, not shown. Secured to the drum 1 is the usual brake drum 2, and co-operating therewith is a brake band 3. Secured to the drum 2 is a gear member 4 adapted to be driven by pinion 5 mounted 50 upon a shaft 6 which is driven by any suitable source of power.

A hand lever 7 is pivotally mounted at one

end upon a rod 12 suitably supported in the 55 main frame 29. There are provided coöperating parts for the hand lever 7, such as the reciprocable member 8 formed with an inner catch portion 9 adapted to coöperate with the notches 11 formed in a suitably 60 supported frame member 10.

Pivots mounted upon the rod 12 is a 65 rocking member 13 formed with two forwardly projecting arms 14. The outer free end of said arms 14 are intersected by a 70 pair of pivotally mounted pins 15. Said pins 15 are also pivotally mounted in one end of a pair of links 16. These links 16 are pivotally mounted at their other ends on a pin 17 secured to one end of the brake 75 band 3. A second pair of links 18, of angular formation, as plainly shown in Figs. 1, 3 and 4, are pivotally secured at one end to a transversely disposed block 19 mounted on a pin 20. Secured in this block 19 and 80 centrally thereof, by means of the pin 20 and nut 21, is a longitudinally disposed tongue member 21, to the forward end of which is pivotally secured the other end of brake band 3 by means of the pin 22. This pair 85 of angular links 18 are pivotally connected by the afore-mentioned pins 15, and at their angles, to the arms 14 of the rocking member 13, and also to the pair of links 16. The other ends of the pair of links 18 are pivotally secured by means of a pin 23 to an arm 24 which is pivotally secured by a pin 26 to a lug formed upon the hand lever 7, the intermediate turn-buckle 25 being also provided for longitudinal adjustment. 90

Suitably mounted in the main frame 29 are a pair of stop members 27 and 28. An adjustable range of action for the elements controlled by said stop members is secured by means of the respective screws 30 and 31, 95 as plainly shown and as will be readily understood.

The automatic action of my differential brake depends upon the functioning of special means which, when the brake drum 100 2 tends to reverse its direction of movement, will bring the ends of the brake band 3 more closely together or more widely space them. This is effected, in general, by making the respective movements of the two ends of the 105 brake band directly proportioned to the different amounts of movement of portions of a pivoted member disposed different dis-

tances from a pivotal axis. In other words, assuming that the brake is loose as shown in Fig. 1, when hoisting is being effected, now if it is desired to suspend the load, and the engine is shut off or the clutch thrown out, and no manipulation of a brake takes place, then the load would tend to drop, tending to rotate the drum 1 in the reverse direction, which would cause the brake drum 2 to rotate in the reverse direction. The consequent frictional contact of the drum 2 and brake band 3 would cause the band to pull downwardly upon the links 16, Fig. 1, which would pull down the coöperating elements arranged around the pair of pins 15. This downward pull would continue until it is terminated by the stop member 27, the efficient gripping of the brake drum 2 by the band 3 having taken place in the meanwhile for the reason now to be given. This reason is, that the links 18 would have pivotally moved upon the pin 23 and the pair of pins 15 to pull down the upper end of the brake band secured to the pin 22. Due to the comparatively greater movement of the outer end of the links 18, as compared with the movement of the section containing the pins 15, the upper end of the brake band 3 would have moved down a greater distance than the lower end thereof, and the result is indicated in Fig. 3, where the brake is set to prevent the reverse action of the drum 2 and thus to suspend the load.

If it is desired to raise the load, the parts being set as shown in Fig. 3, the movement of the drum 2 in the direction of the arrow indicated in Fig. 1 will cause the upper end of the brake band to be raised, which will raise the pins 15 and consequently the link 16. Again, however, the movement of the upper end of the brake band will be proportionately greater than the lower end, resulting in a greater spacing of said two ends of the band, and a consequent loosening of the drum 2 from the frictional contact of the band 3, other than that occasioned by the weight of the band itself. This last mentioned frictional contact is not enough to retard the free movement of the drum 2 and the continued movement of the band 3 is prevented by the stop member 28.

If it is desired to lower the load the drum 2 positively is released from the frictional contact of the band 3 shown in Fig. 3 by means of the actuation of the hand lever 7 from the position shown in Fig. 3 to that shown in Fig. 4, or any other suitable intermediate position. This actuation of the hand lever 7 results in a swinging of the ends of the links 18, pivoted upon the pin 23, about the pins 15, raising the pin 20 and consequently the upper end of the brake band 3 until the member 13 strikes the stop 27. This is accomplished with little or no movement upon the part of the lower end of

the brake band 3, so that the two ends are spaced more widely apart and the drum 2 positively is freed from the band 3.

It is evident that in the above described apparatus, the brake is under control of the operator and is not fixed so that it is necessary to change it with a wrench or similar tool for a new setting. All of the hoisting or suspending can be effected without touching the brake. The only manipulation that is necessary during the hoisting or suspending is to shut off the engine or throw out the clutch, instead of it being necessary to use both hands, as heretofore, to shut off the engine and to manipulate the brake. The range of movement can be adjusted, as desired, by means of the turn buckle 25 and the screws 30 and 31.

What I claim is:

1. A differential brake, comprising a brake drum; a brake band; and means for tightening and releasing said brake band automatically, including a pivotally supported member, a link pivotally secured to said member and pivotally secured to one end of said brake band, and a second link pivotally secured to the other end of said brake band and pivotally secured to said first link intermediately of the two pivotal connections of the latter. 95

2. A differential brake, comprising a brake drum; a brake band; and means for tightening and releasing said brake band automatically, including a link pivotally mounted at one end, means limiting the amount of said pivotal movement, said link being pivotally secured at its other end to one end of said brake band, and a second link pivotally secured at one end to the other end of said brake band and pivotally secured to said first link intermediately of the ends of the latter. 100

3. In hoisting apparatus, the combination of a frame; a cable drum; a brake drum secured to the latter; power means for rotating said cable drum; a brake band; a pin; supporting means for said pin mounted on said frame so as to have a reciprocating movement relative to the latter; a link pivotally secured at one end to said pin and pivotally secured at the other end to one end of said brake band; and a second link pivotally secured at one end to said first link intermediately of the ends of the latter and pivotally secured at its other end to the other end of said brake band. 110

4. In hoisting apparatus, the combination of a frame; a cable drum; a brake drum secured to the latter; power means for rotating said cable drum; a brake band; a pin supported by said frame and free to have a transverse reciprocatory movement relative thereto; an angularly shaped link pivotally secured at one end to said pin and pivotally secured at the other end to one end of said 120

brake band; a second link pivotally secured to said first link at the angle thereof and pivotally secured to the other end of said brake band; a rock arm pivotally mounted 5 in said frame and pivotally secured at one end to said two links; and stop members limiting the movement in both directions of said rock arm.

5. In hoisting apparatus, the combination 10 of a frame; a cable drum; a brake drum secured to the latter; power means for rotating said cable drum; a brake band; a notched member secured to said frame; a hand lever pivotally mounted at one end in 15 said frame and adapted to coöperate with said notched member for setting or releasing; an arm adjustable in length pivotally

secured at one end to said hand lever; a pin mounted in the free end of said arm; a rock arm pivotally mounted in said frame; stop 20 members limiting the movement in both directions of said rock arm; a link pivotally secured to one end of said rock arm and pivotally secured to one end of said brake band; a second link pivotally secured to the other 25 end of said brake band, pivotally secured intermediately its ends to said rock arm and said first link and pivotally secured to the pin mounted in the free end of the above-mentioned arm.

Signed by me this 21st day of October, 30
1919.

HOWARD F. JOHNSON.
